C. B. HALE,
PNEUMATIC SECONDARY CLOCK,
APPLICATION FILED NOV. 23, 1916.

1,335,053.

Patented Mar. 30, 1920.

UNITED STATES PATENT OFFICE.

CHARLES BALLARD HALE, OF PARK RIDGE, ILLINOIS, ASSIGNOR TO TIME SYSTEMS COMPANY, OF DETROIT, MICHIGAN, A CORPORATION OF MICHIGAN.

PNEUMATIC SECONDARY CLOCK.

1,335,053.

Specification of Letters Patent. Patented Mar. 30, 1920.

Application filed November 23, 1916. Serial No. 132,942.

To all whom it may concern:

Be it known that I, CHARLES BALLARD HALE, a citizen of the United States, residing at Park Ridge, in the county of Cook and State of Illinois, have invented new and useful Improvements in Pneumatic Secondary Clocks, of which the following is a specification.

This invention relates to new and useful improvements in secondary clock movements, designed especially for operation by pneumatic impulses whereby the movement is advanced without the usual springs, weights, etc., from a master clock.

Heretofore, in placing movements of this character in the secondary clock casing, it has been necessary to use a plurality of screws, whereby the movement is attached to the interior of the casing. These screws are eliminated by the present invention, and the movement is held fixed within the clock casing without the necessity of more than one attaching element.

It is also the object of the present invention to produce a secondary movement which is not only simple in its construction, but which may be assembled with vastly greater ease than the average clock movement, or pneumatic clock movements prior hereto.

With the above and other objects in view, as will be apparent, this invention consists in the construction, combination and arrangement of parts, all as hereinafter more fully described, claimed and illustrated in the accompanying drawings, wherein:

Figure 1 is a fragmentary interior elevation of a clock dial, illustrating the secondary movement, forming the subject matter of the present invention, attached thereto.

Fig. 2 is a side elevation of the present movement in conjunction with the fragmentary edge elevation of the clock dial.

Fig. 3 is a vertical section taken along line 3-3 of Fig. 1 to illustrate the shaft of the movement and the mounting of the gear train thereon, also the means whereby the movement is held fixed to the dial.

Fig. 4 is an elevation partly in the section of the diaphragm plunger rod through the medium of which the movement is advanced from the diaphragm.

Fig. 5 is a section taken along line 5-5 of

Fig. 1, and illustrates the construction and mounting of the diaphragm cup. 55

Fig. 6 is a transverse section along lines 6-6 of Fig. 5, to illustrate the construction of the diaphragm cup and the mounting and locking of the diaphragm therein, and also the co-operation thereof with the plunger plate. 60

Incident to a clear understanding of the present invention a brief description of the clock system of which it forms a part is desirable. Such a system of clocks, in its preferred form comprises a master clock from which extends one or more line pipes, each line pipe having one or more of the secondary clock movements forming the subject matter hereof, connected in series, 70 thereto. The master clock in its operation sends an impulse of air into the line pipe and maintains this pressure during one minute, at the expiration of which normal or atmospheric pressure is restored in the line 75 pipe. Hence, during one minute a pressure is maintained in the line pipe, and during the next minute atmospheric pressure is restored and so on indefinitely, alternating normal and abnormal pressures in the line 80 pipe.

The present clock movement is designed to be influenced by these alternating conditions so that it will advance one minute when a pressure is produced in the line pipe 85 and another minute when atmospheric conditions are restored. Thus the present movement advances one minute with each change of pressure conditions in the line 90 pipe.

In carrying out the present invention a front plate 10 is provided to rest parallel to and at the rear of the secondary clock dial 11, for the support of the secondary movement. This front plate 10 comprises 95 a normally vertical body 10^b, which at its upper end terminates in the reduced extension 12, and at its lower end in the divergent arms 10^a, extending, at an angle to the body 10 upon each side thereof. In turn the arms 100 10^a terminate in the convergent arms 10^c, which at their point of vergency, create an enlarged surface 13, utilized in carrying the pneumatic operating mechanism to be hereinafter described. Approximately midway 105 of their length the arms 10^c are bent at right

angles so that the supporting surface or platform 13 is at right angles to the front plate 10. It is manifest from the foregoing that the arms 10^a and 10^c in combination 5 form, prior to the bending of said arm 10^c, a substantially skeleton triangle with the supporting surface or platform 13 as its apex.

At the end of the extension 12 of the body 10^b of the front plate 10, and at junctions 10 between the arms 10^a and 10^c are the studs 14, formed from the front plate 10 and extending at right angles thereto on the opposite side thereof to the bent portions of 15 the arms 10^c. When the front plate 10 is positioned on the rear face of the dial 11, these studs 14 rest against the inner face of the dial, and not only space said front plate therefrom, but hold the plate steady and 20 prevent any movement thereof relative to the dial.

In order to removably secure the front plate to the dial and rigidly hold the same in place, the dial 11 is pierced by the usual 25 central opening 15 (Fig. 3) through which passes the exteriorly threaded bushing 16. The end of the bushing 16 projecting beyond the dial face is provided with a washer 17 and has a nut 18 threaded thereon, the 30 washer resting against the dial and the nut clamping firmly against it. At its inner end the bushing 16 enters an opening 19 in the body 10^b of the front plate 10, where it is upset or riveted to the plate. Between the 35 dial 11 and the body 10^b of the front plate 10, the bushing 16 is encircled by the integral and circumferential rib or washer 20, the periphery of which is knurled to form a toothed bur 21 at each end thereof. 40 When the bushing 16 is upset or riveted to the body 10^b of the front plate 10, the bur 21 of the rib or washer 20 adjoining said plate will bite into the same and will thus 45 secure the bushing 16 thereto in such a manner that it cannot turn in the opening 15 of the said plate. As the nut 18 is tightened upon the projecting and threaded portion of the bushing 16, its action will draw the bushing 16 through the opening 15 in the 50 dial 11 until the bur 21 of the rib or washer 20 adjoining the inner side of the dial will bite into the same and hence prevents any 55 rotary movement of the bushing relatively to the dial. Manifestly therefore, the front plate 10 together with the mechanism carried thereby and the dial 11 are to all intents and purposes a unitary structure until such time as the nut 18 and washer 17 are removed from the bushing 16, when the 60 plate 10 may be removed.

The entire secondary clock movement together with its driving mechanism is mounted on the front plate 10, the movement itself centering about the bushing 16. To 65 accomplish this an hour sleeve 22 is mounted

for rotation within the bushing 16 and projects from each end thereof. The escapement or minute shaft 23 is mounted within this hour sleeve 22 in such a manner that it may rotate relatively to the sleeve simultaneously with the latter's movement relative to the bushing 16. At its forward end 70 the escapement or minute shaft projects somewhat beyond the terminal of the sleeve 22, while at its opposite or rear end it projects a comparatively greater distance beyond the corresponding end of said sleeve. The portions of the sleeve 22 and the shaft 23 projecting beyond the forward end of the bushing 16 have the hour and minute hands 75 24 and 25 respectively secured thereto.

The time train is mounted upon the escapement or minute shaft 23, the hour sleeve 22, and a counter shaft 26, the latter being fixed to the front plate 10. Mounted on the escapement or minute shaft 23 is an escape wheel 27, which when advanced operates the entire movement through the medium of the barrel pinion 28 likewise mounted on the shaft 23 and fixed thereto. For its rotation, 80 the inner end of the hour sleeve 22 has a gear 29 keyed or otherwise fixed thereto. The countershaft 26 has loosely mounted thereon the gear 30 and the pinion 31, said gear and pinion operating together as a 85 unit. As the escapement wheel 27 advances step by step the barrel pinion 28 and the escape shaft 23 are rotated correspondingly, hence advancing the minute hand 25. Inasmuch as the gear 30 of the countershaft 26 90 meshes with the barrel pinion 28, and the pinion 31 of said countershaft meshes with the gear 29 of the sleeve 22, the movement of the said barrel pinion will be transmitted to the hour sleeve 22. The ratio of this 95 time train is such that the ratio of movement of the shaft 23 and sleeve 22 is 12 to 1.

A back plate 32 is spaced from the front plate 10 by means of the posts 33 which are secured to said front plate and carry the 100 back plate thereby forming a housing for the time train above described. This back plate 32 also forms a mounting for the escapement or minute shaft 23 and for the pins upon which the escape pawls, to be 105 hereinafter described are mounted.

In order to provide for the escapement or advance of the time train the escape wheel 27 is operated upon by the escape pawls 34 and 35 (Figs. 1 and 2) meshing with the 110 teeth of said wheel upon opposite sides of the upper end of the vertical diameter thereof. The back plate 32 is provided with the divergent extensions 32^a, to form bearings for the outer ends of the pins 36 supported and carried by the front plate 10. These pins or studs 36 constitute indirect supports for the escape pawls 34 and 35. To mount the pawl 35 a bell crank 37 is pivotally mounted on the pin 36 adjoining 115 120 125 130

the position of said pawl 35 so that one arm is normally horizontal and its other arm vertical. The horizontal arm extends to a point medial of the pins 36 where it is bifurcated as at 38, while the vertical arm terminates in an angular tooth 39 located normally at the approximately adjacent corresponding end of the horizontal diameter of the escape wheel 27 and at a point somewhat removed from the wheel 27. The pawl 35 embraces the vertical arm of the bell crank 37 where it is pivoted in any desirable manner, being limited in its downward movement by a stop 35^a projecting at an angle from the pawl to rest against the vertical arm of said bell crank, and thereby maintain said pawl in an approximately horizontal normal position with its free end engaging the teeth of the escape wheel 27.

20 The opposed escape pawl 34 is mounted on the remaining pin 36 in a generally similar manner. A lever 40 is pivoted to the remaining pin 36, and extends across the vertical diameter of the escape wheel 27, where it terminates in the tooth 41 angularly arranged with respect to the lever and similar to the tooth 39 of the bell crank 37. The pawl 34 embraces the lever 40 medially of its length, where it is pivoted in such a manner that its free end engages the teeth of the escape wheel 27; the downward movement of said pawl being limited by a stop 34^a, which extends at an angle to the pawl and normally rests against the body of the lever 40.

To provide for the simultaneous operation and co-action between the pawls 34, 35 and of necessity the bell crank 37 and lever 40, the latter is provided with an extension 42 which terminates adjacent to and overlaps the bifurcated end 38 of the bell crank 37. This extension has an outstanding pin 43, so located that it is received in the bifurcation 38, thereby connecting the bell crank 37 to the lever 40 whereby the oscillation of one is transmitted to the other.

A second pin 44 is carried by the extension 42, and is encircled midway of its length by the circumferential double conical bead or rib 45, provided to removably secure the operating plunger rod 46 (to be described) to the lever 40, in order that it may through its reciprocation oscillate the lever 40 and the bell crank 37.

55 From the foregoing it is manifest that when the plunger rod 46 moves upwardly it will apply a lifting force to the pin 44, thereby moving the lever 40 and horizontal arm of the bell crank 37 upwardly. This movement causes the vertical arm of the bell crank lever to swing inwardly and bring the tooth 39 thereof into direct engagement with the teeth of the escape wheel 27 but not however, before the pawl 35 has exerted a pressure on one of the teeth of said wheel to

advance the time train so that the hands may be moved to indicate the passage of one complete time unit. Simultaneously with this movement, the tooth 41 of the lever 40 becomes disengaged from the teeth of the escape wheel 27, and the pawl 34 rides over the periphery of said wheel to engage the next adjacent tooth thereof.

When the plunger rod 46 moves downwardly at the expiration of a unit of time, 75 the lever 40 and horizontal arm of the bell crank 37 oscillate in similar direction, causing the pawl 34 to exert a pressure on the tooth of the escape wheel 27 engaged thereby and immediately thereafter bring the tooth 80 41 of said lever into engagement with the teeth of said escape wheel; thus the time train is advanced or escaped a unit of time. While this is being done the tooth 39 at the end of the vertical arm of the bell crank 30 85 90 is removed from engagement with the periphery of the escape wheel 27, and the pawl 35 permitted to ride over the periphery of said wheel 27 to engage the next adjacent tooth thereof, in order that it may be prepared to advance the time train to indicate the next unit of time.

Therefore it is clear that the plunger rod 46 reciprocates once during the passage of two units of time, *i. e.:* it moves upwardly 95 at the expiration of one unit and downwardly at the expiration of the next unit, said rod remaining in the position to which it is moved during the passage of one unit of time. This action is continually repeated, 100 thus advancing the time train alternately by the pawls 34 and 35, the teeth 39 and 41 acting as stops to insure accuracy of movement on the part of the time train.

Hereinbefore it has been described how 105 the master clock with which one or more of the present movements coöperate, alternately places a pressure in the line pipe at the expiration of one unit of time and maintains such pressure during one time unit, 110 115 at the expiration of which the line pipe is returned to atmospheric pressure during the passage of the next unit of time. When the line pipe is under pressure the plunger rod 46 moves upwardly and when atmospheric conditions are restored the rod moves downwardly, and consequently for each change of pressure conditions within the line pipe the secondary movement advances or escapes.

To accomplish this, the supporting surface platform 13 of the front plate 10 is pierced by an aperture 47 communicating with a slot 48 extending to the edge of said platform or surface the width of which is somewhat less than the diameter of the 125 aperture 47. The platform or surface 13 at one side of the slot 48 has a projection 49 formed therefrom the edge of which rests approximately parallel to the edge of the slot 48. Mounted on the platform or sup- 130

porting surface 13 is the diaphragm cup C, the bottom of which has the outwardly extending nipple 50 secured concentrically thereto, the passage 51 of said nipple communicating with the interior of the cup C. Flush with the bottom of the cup C, the nipple 50 is provided with a faced flange 52 which when the cup C is on the platform 13 rests flush against said platform with one face engaging the projection 49, thereby preventing the cup C and nipple 50 from turning or rotating within the aperture 47. Directly below the faced flange 52 the nipple 50 has an exteriorly threaded cylindrical portion 53, of a such diameter that it may readily pass through the aperture 47 in the supporting platform or surface 13, but not through the slot 48 communicating therewith. This threaded cylindrical portion 53 projects below the supporting platform or surface 13 where it is engaged by the winged nut 54 adapted when in position to rest flush against the under side of said platform 13, and clamp it securely between the bottom of the cup C and the said nut, thereby removably but securely fastening the cup C to the platform below the time train. At a point below the threaded portion 53 the nipple 50 is reduced as at 50^a to a diameter sufficient to pass through the slot 48 in the platform 13; hence by loosening the wing nut 54 and raising the cup C to disengage the threaded portion 53 of the nipple 50 from the aperture 47 of the platform 13, the reduced portion 50^a may be passed through the slot 48 to remove the cup C aforesaid from the platform. The nipple 50 is connected with the pipe 55 which communicates with the line pipe (not shown), and by this means all changes of pressure in the line pipe are transmitted to the diaphragm cup C through the pipe 55 and the passage 51 of the nipple 50.

Upon the bottom of the diaphragm cup C is placed a flexible lining 56 of rubber or other suitable material (Fig. 6) which completely covers said bottom. This lining 56 has a concentric opening 57 therein which registers with the upper end of the passage 51 through the nipple 50. Over this is placed the imperforate flexible diaphragm 58 which under atmospheric pressure rests flush upon and coincides with the lining 56. The coinciding circumferences of the lining 56 and the diaphragm 58 are held together in a substantially air tight seal by means of the vertical clamping ring 59 operating upon the said edges, a flexible washer 60 being interposed between the ring 59 and the edge of the diaphragm 58.

To hold the clamping ring in place and to force it against the diaphragm 58 and the lining 56, the wall of the cup C is provided with a plurality of downwardly oblique slots 61 over which the ring 59 partially

laps, access being had to the slot 61 through the vertical entrance slots 62, extending to the edge of the wall. A clamping plate 63, comprising a ring 63^a, having the diametrical crossbar 63^b and the outstanding studs 63^c is adapted to rest upon the upper edge of the ring 59 with its studs 63^c in the slots 61 of the wall of the cup C said studs having reached the slots through the entrance slots 62. By grasping the cross-bar 63^b and turning the clamping plate 63 thereby, the studs 63^c will ride down the slots 61 and by the same action thereof will force the ring 59 downwardly, clamping the lining 56 and the diaphragm 58 together forming a substantially air tight seal between these two elements.

It is therefore clear that when an abnormal pressure is created in the line pipe and the pipe 55 the diaphragm 58 will move upwardly to the dotted line position in Fig. 6, forming an ellipse in combination with the lining 56 and the bottom of the cup C, and when atmospheric pressure is restored in these pipes the diaphragm will drop or return to its full line position. It should be here observed that the bottom of the cup C is convexed outwardly, and thus forms an approximate reverse curve to the curve of the diaphragm 58 when the same is raised or distended. This allows a maximum movement on the part of the diaphragm, which may be limited by the adjustment of the plunger rod 46, to be presently described.

To impart the movement of the diaphragm 58 to the plunger rod 46 and through the medium of the latter to the bell crank 37 and lever 40 a plunger plate 64 rests upon said diaphragm and partakes of its movement. This plate 64 has a stud 65 swiveled thereto, said stud being reduced as at 66 where it joins the plate 64 and at its upper is again reduced as at 67, the latter reduction being exteriorly threaded. The cross bar 63^b of the clamping plate 63 is provided with a guide opening 68 of a diameter sufficient for the stud 65 to reciprocate therethrough. This guide opening 68 severs an adjacent edge of the cross bar, creating a means of access to the opening of less width than the diameter of said opening by means of which the stud 65 may be placed in said opening when the plate 63 is in place, the reduced portion 66 being used for this purpose.

The threaded reduction 67 of the stud 65, screws into the lower end of the plunger rod 46, the latter being a tube, thus providing an adjustment between the rod 46 and said stud. Inasmuch as the stud 65 is swiveled to the plunger plate 64 and is externally knurled as indicated, any rotation of said stud will lengthen or shorten the plunger rod as an entity provided of course, that the portion 46 thereof is held from turning.

When the relative positions of the stud 65 and rod 46 have been determined a lock nut 69 may be rotated until it bears against the lower end of the rod 46 thus fixing the adjustment.

At its upper end the rod 46 is split as at 70 (Fig. 4) each side of said split having a semi-circular depression therein. A certain amount of resistance is obtained between the 10 sides of the split 70, hence by placing the end of the pin 44 in the opening formed by the combination of the depressions 71 and forcing the upper end of the rod 46 toward the back plate 32 the sides of the split will 15 ride over the double conical flange or rib 45, removably locking the latter within the upper end of the tube 46. By merely pulling on the upper end of the rod 46 the same may be quickly disengaged from the pin 44. 20 The feature is extremely useful in removing the plunger rod 46, and plate 64 when it is desired to change the diaphragm, the attachment or detachment being instantaneous.

As the diaphragm 58 is affected by the 25 various pressure conditions in the line pipe, so are the plunger plate 64 and the plunger rod 46 affected, the movement thereof operating the time train as heretofore described.

30 In order to set the hands, the inner end of the escapement or minute shaft is provided with a knurled flange 72, by means of which said shaft may be rotated in either direction.

35 While the preferred form of the present invention is illustrated and described it is to be understood that many changes may be made in details of construction without departing from the spirit and scope thereof.

40 What is claimed is:—

1. The combination with a plate, having studs formed therefrom and extending from one side of said plate and a platform formed from and extending from the other side of 45 said plate, of a dial coöperating with said plate and spaced therefrom by the studs aforesaid.

2. The combination with a plate, having studs formed therefrom and extending from one side of said plate and a platform formed 50 and extending from the other side of said plate, of a dial coöperating with said plate and spaced therefrom by the studs aforesaid, and means carried by the plate for piercing 55 said dial to removably secure the plate to the dial aforesaid.

3. The combination with a dial, of a plate coöperating therewith, a series of studs extending therefrom and bearing against the 60 dial aforesaid, and means carried by the plate for securing the same to the dial.

4. The combination with a dial, of a plate coöperating therewith, a series of studs extending therefrom and bearing against the

dial aforesaid, and means carried by the 65 plate for securing the same to the dial, including means to prevent a rotary or lateral displacement on the part of the plate.

5. The combination with a dial, of a movement carrying plate coöperating therewith, a series of studs projecting from said plate to rest against said dial. 70

6. The combination with a dial, of a movement carrying plate coöperating therewith, a series of studs projecting from one 75 side of said plate to rest against said dial, and a bushing fixed to said plate and adapted to pierce said dial.

7. The combination with a dial, of a movement carrying plate coöperating therewith, a series of studs projecting from one 80 side thereof for contact with said dial, a bushing carried by said plate and adapted to pierce said dial, attaching means for securing the end of the bushing projecting 85 through the dial, and means interposed between and engaging the dial and plate for locking said plate from displacement.

8. The combination with a dial, of a movement carrying plate coöperating therewith, a series of studs projecting from one 90 side thereof for contact with said dial, a threaded bushing carried by the plate and adapted to project through the dial, a nut on the projecting end of said bushing for 95 securing it and the plate to the dial, and means interposed between the plate and dial adapted to engage both said plate and dial to lock the former against movement relative to the latter. 100

9. The combination with a dial, of a movement carrying plate coöperating therewith, a series of studs projecting from one 105 side thereof for contact with said dial, a threaded bushing carried by the plate and adapted to project through the dial, a nut on the projecting end of said bushing for securing it and the plate to the dial, and a rib formed on said bushing between said plate and dial in the space created by said 110 studs, said rib having its periphery knurled to form two burs, one for biting into the plate and the other into the dial upon the tightening of the nut aforesaid.

10. The combination with a dial, of a 115 plate coöperating therewith, a bushing for securing said plate to said dial, and means interposed between the dial and plate for engaging both.

11. The combination with a dial, of a 120 plate coöperating therewith, a bushing for securing said plate to said dial, and a rib encircling said bushing having a bur projecting from each side thereof for engagement with the plate and dial aforesaid to 125 eliminate any relative movement thereof.

12. The combination with a dial, of a plate coöperating therewith, a bushing for

securing said plate to said dial, a nut threaded upon said bushing, and a rib encircling said bushing.

13. The combination with a plate, of a supporting platform carried thereby, having an opening therein communicating with the edge of said platform by a slot of less width than the diameter of the opening, a diaphragm cup removably supported by said platform, and a nipple on said cup arranged to be received in said opening and having a reduction capable of passing through the slot aforesaid.

14. The combination with a plate, of a supporting platform carried thereby, having an opening therein, a diaphragm cup carried by said platform, a nipple on said cup arranged to be received in the opening, and means for holding said nipple and cup from rotary movement relative to the platform aforesaid.

15. The combination with a plate, of a supporting platform carried thereby, having an opening therein, a diaphragm cup carried by said platform, a nipple on said cup arranged to be received in the opening, a projection on said platform adjoining the opening thereof, and means carried by the cup and nipple for coöperation with said projection.

16. The combination with a plate, of a supporting platform carried thereby, having an opening therein, a diaphragm cup carried by said platform, a nipple on said cup arranged to be received in the opening, a projection on said platform adjoining the opening thereof, and a faced flange carried by the cup and its nipple for coöperation with said projection to retain said cup and nipple from any rotary movement relative to the platform aforesaid.

17. The combination with a supporting platform, having an opening therein communicating with the edge of the platform by means of a slot, a diaphragm cup, and a nipple projecting from said cup, said nipple varying in diameter, whereby one portion thereof may be engaged by the opening and another pass through the slot aforesaid upon disengaging the first portion from said opening.

18. The combination with a supporting platform, having an opening therein communicating with the edge of the platform by means of a slot, a diaphragm cup, a nipple projecting from said cup, having an exteriorly threaded enlargement to project through said opening, terminating in a reduced portion arranged to pass through said slot upon the disengagement of the enlargement from the opening, and a winged nut adapted to be threaded upon the projecting end of the enlargement of the nipple.

19. The combination with a supporting platform, having an opening therein communicating with the edge of the platform by means of a slot, a diaphragm cup, a nipple projecting from said cup, having an exteriorly threaded enlargement adapted to project through said opening, terminating in a reduced portion arranged to pass through said slot upon the disengagement of the enlargement from the opening, a projection on said platform adjacent to said opening, a faced flange on said nipple for coöperation therewith when the enlargement thereof is in said opening, and a winged nut adapted to be threaded on the projecting end of the enlargement when projecting through the opening aforesaid.

CHARLES BALLARD HALE.
